his attorney.

UNITED STATES PATENT OFFICE.

WILLIAM REAVELL, OF IPSWICH, ENGLAND.

HYDROPLANE OR HORIZONTAL RUDDER OF SUBMARINE VESSELS.

1,343,643.

Specification of Letters Patent. Patented June 15, 1920.

Application filed October 14, 1918. Serial No. 258,045.

To all whom it may concern:

Be it known that I, WILLIAM REAVELL, a subject of the King of Great Britain and Ireland, residing at Ipswich, in the county 5 of Suffolk, England, have invented Improvements Relating to the Hydroplanes or Horizontal Rudders of Submarine Vessels, of which the following is a specification.

This invention has reference to improvements in means for folding the hydroplanes or horizontal rudders of submarine vessels into such positions against the superstructure or hull of the vessel as to reduce the resistance they offer to the progress of the vessel when running on the surface, and for restoring them to their working positions when about to dive. The main object is to provide comparatively inexpensive and simple mechanism adapted to quickly move the 15 planes or rudders from the one position to the other.

According to the present invention, the planes or rudders are connected at their inner edges by pivots, which are parallel with the planes or rudders to the ends of a transverse rock shaft mounted in bearings on the upper part of the hull of the vessel and are linked to nuts through which extend the oppositely threaded end portions of a shaft that 25 is held in bearings parallel to the plane or rudder carrying shaft, the said threaded shaft being rotatable so as to draw the nuts together or move them apart and thus fold the planes or rudders or turn them into their 30 working positions, when the shaft by which they are carried can be rocked and the rudders tilted in the required direction without interfering with the folding gear.

Referring to the accompanying drawings, 40 Figure 1 is a section partly in elevation illustrating the gear.

Fig. 2 is a part plan view the lower half being in section, of the connections of the gear with one of the rudders.

45 Fig. 3 is a transverse section on the line A, A, Fig. 1; and Fig. 4 is a transverse sectional elevation on the line B B Fig. 1.

50 *a* is the hull of the vessel, *b* the transverse plane or rudder carrying rock shaft formed with enlarged ends *b*¹ through which extend the pins *c* by which the rudders *d* are pivoted to the shaft *b*; *e* *e* are the bearings secured to the hull *a* in which the shaft *b* is mounted and *f* *f* are housings fixed to the shaft *b* by keys *g* and formed with bearings *f*¹ in which is mounted a shaft *i* that con-

veniently may be actuated through gearing comprising a spur wheel *j* freely mounted on the shaft *b* and engaging a spur wheel *k* keyed on the shaft *i*. The spur wheel *j* may 60 be rotated through bevel gear *l* and a shaft *m* as shown, or by worm gear. On the oppositely threaded end portions of the shaft *i* are nuts *n* contained within the housing; each nut is formed with trunnions *n*¹ extending through slots in inner walls *f*² in the housings and pairs of links *o* connect the trunnions of each nut to a pin *p* on the corresponding plane or rudder. In the drawings the planes or rudders are shown as folding upward or turning upwardly about their inner edges into the position shown at the right hand side of Fig. 1, and, although for the purposes of illustration, the plane or rudder at the left hand side of Fig. 1 is 70 shown in the working position it will be understood that the two planes move together into the working or stowed positions; when in the working position a flat on the plane or rudder abuts against a flat on the enlarged end of the shaft *b* as shown at *x*, Fig. 1.

The shaft *b* can be rocked by any suitable mechanism when it is required to tilt the planes or rudders; for instance a worm sector on the shaft and a worm actuated from within the hull of the vessel. Preferably however, there is keyed to the shaft *b* a lever *q* through an eye in which the threaded shaft *i* passes freely, and the extremity of 80 this lever is engaged by a rod which passes into the hull of the vessel and is there actuated by any suitable mechanism to give the required tilting motion to the planes.

The planes or rudders may be arranged to 95 be folded upward into recesses in the superstructure, or they may be arranged to fold downward against the hull, the parallel shafts and the link connections being arranged accordingly.

100 What I claim is:—

1. Hydroplanes or horizontal rudders for submarine vessels connected at their inner edges by pivots, which are parallel with the planes or rudders to the ends of a common 105 transverse rock shaft mounted in bearings on the upper part of the hull of the vessel, in combination with means for rocking said shaft and means for turning the planes or rudders about their inner edge pivots into 110 and out of their working positions, substantially as described.

2. Hydroplanes or horizontal rudders of submarine vessels connected by pivots which are parallel with the planes or rudders to the ends of a transverse rock shaft mounted 5 in bearings on the upper part of the hull of the vessel and linked to nuts through which extend the oppositely threaded end portions of a shaft that is held in bearings parallel to the plane or rudder carrying shaft, the said 10 threaded shaft being rotatable so as to draw the nuts together or move them apart and thus turn the planes or rudders about their pivots out of or into their working positions substantially as described.
- 15 3. Hydroplanes or horizontal rudders of submarine vessels pivoted to the ends of a transverse rock shaft mounted in bearings on the upper part of the hull of the vessel and linked to nuts through which extend the 20 oppositely threaded end portions of a shaft that is held in bearings parallel to the plane or rudder carrying shaft, the said threaded shaft being rotatable so as to draw the nuts together or move them apart and thus fold 25 the planes or rudders or turn them into their working positions by means of gearing com-

prising intermeshing spur gears, the one freely mounted on the plane or rudder carrying shaft and adapted to be actuated through suitable gears and the other fixed to 30 the threaded shaft, substantially as described.

4. The combination of hydroplanes or horizontal rudders of a submarine vessel with a transverse rock shaft to the ends of 35 which said hydroplanes or rudders are pivoted, bearings on the upper part of the hull of the vessel in which said shaft is mounted, nuts to which the planes or rudders are linked, an oppositely threaded shaft extending 40 through said nuts, housings fixed upon the rock shaft and containing said nuts, bearings in said housings for the threaded shaft parallel to said rockshaft, intermeshing spur gears fixed on the threaded shaft 45 and freely mounted on the rock shaft, means for actuating the latter spur gear, and means for rocking the transverse rock shaft, substantially as described.

Signed at Ipswich, Suffolk, England, this 50
19th day of Sept., 1918.

WILLIAM REAVELL.
